UNITED STATES PATENT OFFICE.

EDWARD H. HOPSON, OF BROOKLYN, NEW YORK, ASSIGNOR TO MERRITT & CHAPMAN DERRICK & WRECKING COMPANY, OF NEW YORK, N. Y., A CORPORATION OF WEST VIRGINIA.

PILE-DRIVING APPARATUS.

Application filed November 15, 1919. Serial No. 338,259.

To all whom it may concern:

Be it known that I, EDWARD H. HOPSON, a citizen of the United States, and a resident of the borough of Brooklyn, city of 5 New York, and State of New York, have invented an Improvement in Pile-Driving Apparatus, of which the following is a specification.

My invention relates to apparatus for 10 driving piles and is particularly designed for use in driving piles which are to terminate below water level. The object of my invention is to provide an apparatus of this sort which will be of improved construction 15 and facilitate such pile driving.

In this specification I have disclosed for 20 purpose of illustration one form which my invention may assume. In the drawings accompanying this specification and showing this illustrative embodiment:

Figure 1 represents a general view of my entire device,

Figure 2 represents a cross-section of the 25 apparatus on the line 2—2 of Figure 1, Figure 3 represents a vertical detailed section taken along the line 3—3 of Figure 2,

Figure 4 represents a front elevation of the section of the apparatus disclosed in 30 Figures 2 and 3 viewed from a direction at right angles to the direction of view in the section of Figure 3,

Figure 5 represents a top view of the 35 part shown in Figure 4 but with the detachable head removed,

Figure 6 represents a side elevation of the structure disclosed in Figure 5,

Figure 7 represents a detail of the foot, 40 while

Figure 8 represents a detail of the following.

My invention comprehends the use of any suitable base such as the scow 21, any suitable pile driving derrick thereon such as 45 the derrick generally illustrated at 22, and any suitable means for operating the driving weight or hammer 23 such as the power plant indicated generally at 24. In utilizing my invention I may provide the scow 50 21 with a suitable well 25 through which my guide may extend.

As herein illustrated, my pile guide may consist of a head section 26 and a strut or column 27 and to this column may prefer- 55 ably be appended a foot 28. The head 26

may be constructed in any suitable manner but is preferably provided with means providing facilities for the reception of raising and lowering cables 30, and this means may consist of plates 31 suitably secured to the head and provided with sheaves 32 about which the cables are looped. This head may also be provided with suitable angular extensions 33 adapted to slide along the hammer slides 34 and thus guide the head 26 when it is raised and lowered. The use of the hammer slides 34 for this purpose is important inasmuch as it saves duplication of slides and appreciably lessens both the cost and weight of the construction. 70

I provide means for securing the head to the column member in a suitable manner and this means may comprise bolts 35 as illustrated in Figure 3. The column member 27 may be constructed in any desired manner although I prefer to use a fabricated structure similar to that disclosed in the drawings and particularly shown in Figures 4, 5, and 6. This column member may be provided with four longitudinally extending angles 36 the pairs of which form grooves or tracks 37 which are designed to cooperate with suitable blocks 38 projecting from the sides of the well 25 and serving in this way to guide the column. I prefer to secure to this column 27 near the bottom end a foot 28 which preferably comprises a flat area 39 of sufficient size to support the guide and at least partially remove the weight thereof from the scow 21. This foot may be braced to the column in any desired manner such as by the upper braces 40 and the lower braces 41. Preferably the foot is placed a short distance above the bottom of the column so that the column 95 will extend below the foot into the bottom for a sufficient distance as shown at 43 to thus prevent lateral motion of the lower end of the column while the pile is being started. The column 27 may be provided with a 100 tube 42 preferably extending, when the guide is in lowered position, from a point above the surface of the water to a point substantially as low as the upper surface of the fully driven pile and of a diameter 105 sufficient to accommodate the pile therein. This tube may be supported from the column in any suitable manner.

In operation, the scow 21 will be moved to the desired position and the column then 110

lowered until it engages the bottom as clearly shown in Figure 1. In this position the foot 28 will relieve the scow from the greater part of the weight of the guide while the column extension 43 will prevent the guide from shifting along the bottom. During this lowering motion the head 26 is continuously guided by the cooperation between the channel 37 and the blocks 38. When the guide has been lowered into position I may detach the head 28 from the column 27 so that the guide is connected to the scow only by the cooperation of the channels 37 and blocks 38.

15 In extremely smooth water or operating with the guide lowered into almost extreme position it may not be necessary to thus disconnect the head 28 but under other conditions such disconnection is almost necessary 20 to prevent rupture from undue strains arising from the rocking of the scow and at all times such disconnection of the head 26 is advisable. In order to further provide for considerable play between the guide and the 25 scow I have so formed the blocks 38 that they fit very loosely in the channels 37. After the guide is in position and the head 26 has been removed (if its removal is desired), a pile is suitably lowered into the 30 sleeve 42 and the pile driver then operated. During the driving operation the pile is guided and held in upright position by means of the sleeve 42.

When the pile has been driven to the surface of the water, or if the length of the pile is less than the depth of the water, it becomes inexpedient to permit the hammer to strike the pile directly due to the excessive resistance of the water which must be traversed by the hammer before engaging the pile. Accordingly, at this point in the driving operation a follower is introduced above the pile and thereafter the driving impact is transmitted to the pile by means of this 45 follower.

This follower may be composed of an iron tube 50 completely filled with a wood core 51 which is preferably in one piece snugly fitting the tube 50 and bolted thereto at frequent intervals by suitable bolts 52. The lower end of the follower may be closed by an iron cap 53 formed to surround the tube 50 and bolted to the tube 50 and filler 51 by one of the bolts 52. This cap may be 55 screw threaded to the tube if desired. The upper end of the follower may be closed by a cap 54 similar to the cap 53 but preferably provided with a reinforcing boss 55 to receive the blow of the hammer. This follower 60 is continually held in position in engagement with the upper end of the pile by the sleeve 42.

By means of the follower the driving op-

eration is continued until the head of the pile is at the elevation desired whereupon 65 the follower is removed and the guide raised and moved into position for driving the next pile. I prefer to employ the follower itself to determine the height of the head of the pile and for this purpose mark the surface of the follower with a series of indications 56. The follower is then used as a transit rod and the elevation of the head of the pile determined according to usual surveying practice. 75

It will be apparent from a consideration of the description of this illustrative form of my invention that I have provided improved means for driving piles and that this means is particularly applicable and 80 effective in those driving operations where the pile must be located with precision and the head of the fully driven pile must be at a definite level substantially below the surface of the water. 85

There are uses for my pile driving apparatus and advantages therein other than those which have been specifically pointed out and there are embodiments and modifications other than those herein illustrated. 90 These uses, advantages, embodiments, and modifications are all embraced in my invention, especially as they may be included in the appended claims. 95

I claim:

1. In a pile driving apparatus, a float, a derrick thereon having vertical ways, a pile driving hammer operatively mounted in said ways, a pile guide movable vertically in said ways and guiding means connecting said pile guide and float, operative to permit a relative rocking movement between said pile guide and float while maintaining driving relation between the pile and hammer. 100

2. In a pile driving apparatus, a float, a driving hammer operatively mounted thereon, a pile guide connected to the float and movable vertically relative thereto, a follower movable in said pile guide and guided thereby, guiding means connecting said pile 110 guide and float to permit relative rocking movement while maintaining operative driving relations and additional guiding means arranged to guide the pile guide during its vertical movement and arranged to be disconnected at will. 115

3. In a pile driving apparatus, hammer ways, a hammer, a pile guide, means whereby said pile guide may slide on said ways, and means whereby said guide may be disconnected therefrom during driving operations. 120

In testimony whereof, I have signed my name to this specification this 13th day of November, 1919.

EDWARD H. HOPSON.
